CLAIM

The ornamental design for an electric toothbrush head and handle unit, as shown and described.

DESCRIPTION

FIG. 1 is a perspective view of an electric toothbrush head and handle unit showing my new design;

FIG. 2 is right side elevational view thereof, the opposite side being a mirror image;

FIG. 3 is a rear elevational view thereof;

FIG. 4 is a front elevational view thereof;

FIG. 5 is a top plan view thereof; and,

FIG. 6 is a bottom plan view thereof.

The broken line showing of bristles is for illustrative purposes only and forms no part of the claimed design.
